MARINE CRAFT

Solon T. Dunlap and Carl Henry Stratton,
Oklahoma City, Okla.

Application August 1, 1935, Serial No. 34,282

2 Claims. (Cl. 114—61)

This invention appertains to new and useful improvements in marine craft and more particularly to a craft of small capacity such as are customarily used for short trips by sportsmen and other pleasure seekers.

The principal object of the invention is to provide a boat of this character which because of its unique construction is practically incapable of accidental capsizing or sinking.

10 Another important object of the invention is to provide a boat of the character stated which will be streamlined in such a manner as to include swiftness with its safety.

Other important objects and advantages of the 15 invention will become apparent to the reader of the following specification.

In the drawings:

Figure 1 represents a top plan view of the 20 craft.

Figure 2 represents a side elevational view of the 25 craft.

Figure 3 represents an enlarged fragmentary bottom plan view of the aft portion of the craft.

Figure 4 represents a sectional view taken substantially on line 4—4 of Figure 1.

Figure 5 represents a sectional view taken substantially on line 5—5 of Figure 1.

Figure 6 represents a sectional view taken substantially on line 6—6 of Figure 1.

Figure 7 represents an elevational view of one 30 of the brace holders.

Referring to the drawings wherein like numerals 35 designate like parts, it can be seen that the hull is denoted by numeral 5 and is of cylindrical construction and provided with pointed end portions 6—7, bow and stern respectively.

As is shown in Figure 4, the bottom of the boat 40 terminates inwardly of the pointed stern 7 and at this point is provided with an upstanding wall 8 on which an outboard motor can be installed, the bottom portion of the stern 7 being open as at 9 to accommodate the outboard motor.

The two passenger compartments denoted by 45 numerals 10—11 are each provided with the upstanding surrounding walls 11 provided with rubber covered edges 12. Brace members 13 span the inside of the hull as in the manner shown in the drawings.

50 At the bow of the hull 5, a stabilizer 14 is provided and on both the port and starboard sides of the hull are the pontoons 15—15.

Secured to each side of the hull 5 are plates 55 16 each provided with an upper and lower socket 17—18. Rods or pipe sections 19—20 extend

from each of the plates 16 to connect to the top and inner side, respectively, of the adjacent pontoon 15 in the manner as shown in Figure 6. The other ends of the rods 19—20 are disposed in sockets 21 on a split clamp band 22 circum- 5 scribing snugly the adjacent pontoon 15.

The top sockets 21 on the clamp band 22 of each pontoon are connected by longitudinal rod portions 23, Figures 1, 2 and 6. It will also be apparent from Figures 1, 2 and 6, that the rod 10 portions 23 extend from the forward sockets 21 and are suitably connected to the forward portion of the hull 5 at opposite sides thereof. Thus the pontoons are firmly braced with respect to the hull and it will also be observed that while 15 the pontoons are shorter than the hull 5, they are pointed at both their bow and stern ends as shown clearly in Figure 2.

It will also be apparent that the rod portions 23 are connected at intermediate points 30 to 20 the pontoons 15 so as to lend increased stiffness and strength thereto, and that said rod portions 23 constitute hand-holds for a person who may fall into the water near one of the pontoons.

The intermediate connections 30 complementary to the rod portions 23 are not essential, and for this reason the intermediate connections, as 25 30, are omitted from Figure 1 of the drawings.

Each of the pontoons 15 is preferably provided, as shown only in Figure 1, with platforms 35 30 from which a person can dive or fish.

While the foregoing specification sets forth the 35 invention in specific terms, it is to be understood that numerous changes in the shape, size and materials may be resorted to without departing from the spirit and scope of the invention as claimed hereinafter.

Having thus described the invention, what is claimed as new is:

1. A craft of the kind described, comprising a 40 hull, upper and lower lateral socket members carried at the opposite sides of the hull at intervals in the length thereof, pontoons at opposite sides of and spaced from the hull, socket members carried at the inner sides and tops of 45 the pontoons in transverse alignment with the socket members of the hull, rods interposed between the hull and pontoons and disposed in the socket members thereof, and longitudinal rods carried by the top socket members of the pontoons and spaced above the pontoons and having their forward portions extended inwardly toward and connected with opposite sides of the hull.

2. A craft of the kind described, comprising a 50 hull, pontoons at opposite sides of and spaced 55

from the hull, transversely disposed rods interposed between the hull and the tops of the pontoons and connected therewith, other transversely disposed rods interposed between and connected with the sides of the hull and the sides of the pontoons, and longitudinal rods spaced above

the pontoons and connected therewith and having end portions connected with opposite sides of the hull.

SOLON T. DUNLAP.

CARL H. STRATTON.
